UNITED STATES PATENT OFFICE.

THOMAS H. HALLIDAY, OF BROOKLYN, ASSIGNOR TO NAT H. VAN WINKLE,
OF NEW YORK, N. Y.

SPRING-BED.

SPECIFICATION forming part of Letters Patent No. 320,552, dated June 23, 1885.

Application filed August 7, 1884. (No model.)

To all whom it may concern:

Be it known that I, THOMAS H. HALLIDAY, a citizen of the United States, residing in Brooklyn, in the county of Kings and State of New York, have invented a new and useful Improvement in Spring-Beds, of which the following is a specification.

The object of my invention is to provide a bed-bottom or mattress which can be fitted to bedsteads of different sizes; and I accomplish this by means of an arrangement of parallel slats, double-jointed arms, guide-bars, braces, and spiral springs, as hereinafter set forth in detail, and illustrated in the accompanying drawings, in which—

Figure 1 is a plan view of the bed-bottom extended. Fig. 2 is a plan view of the same shut up. Fig. 3 is a side elevation of a portion of the same. Fig. 4 is an end section on the line *x x* in Fig. 1.

Similar letters refer to similar parts in the several views.

A are parallel slats forming the frame-work upon which the spiral springs *D* rest.

B are upper outside slats, which rest upon the springs *D*, and which are also connected with the frame-work formed by the slats *A* by means of the supporting-brace *E*, which is pivoted at one end to the upper slats, *B*, and at the other end to the double-jointed arms *C*, which are in turn pivoted to the slats *A* and to each other in such a manner that said slats can be moved toward or away from each other. The arms *C* are also extended beyond the outside slats, *A*, until they meet the guide-bar *F*, having slots *a*. The ends of the arms *C* are so attached to the bar *F* by means of bolts and washers as to permit motion in the slots *a* in a direction parallel to the slats *A*.

For purposes of shipment and before use the bed-bottom assumes the position shown in Fig. 2, the slats and the guide-bars being pressed close to each other, and the jointed arms and braces being nearly parallel with said slats and guide-bars. When fitted to a bedstead, the slats are drawn apart to the

requisite width, and the jointed arms and braces take a position more nearly at right angles to the slats and guide-bars.

The double-jointed arms insure regular and perfect motion, so that it is impossible when the slats are opened and closed for the bed-bottom to get out of working order, which frequently happens in the case of single links or arms.

The guide-bar prevents any twist or endwise motion of the bed-bottom, because the slots *a* hold the ends of the jointed arms firmly in position. The guide-bar also forms a leverage in closing up the slats. Although only one bar is shown in the drawings, an additional one or more may be used, if desired.

The braces *E* moving in unison with the double-jointed arms *C* keep the upper slats, *B*, at the same relative distance from each other in opening and closing the bed-bottom, and also keep them at all times exactly the same distance from the lower slats, *A*.

The whole forms a neat and effective bed-bottom or mattress, with all the parts arranged to insure economy of space and perfect motion without liability of derangement.

What I claim as new, and desire to secure by Letters Patent, is—

1. In a bed-bottom, the combination of the lower slats, *A*, spiral springs *D*, double-jointed arms *C*, upper slats, *B*, and braces *E*, pivoted at one end to the joints of the double-jointed arms *C*, and connected with the upper slats, *B*, as and for the purpose specified.

2. In a bed-bottom, the combination of the lower slats, *A*, springs *D*, upper slats, *B*, braces *E*, pivoted to the slats *B*, and the arms *C*, the double-jointed arms *C* pivoted to each other and to the slats *A*, and the guide-bar *F*, with slots *a*, all arranged substantially as described, and for the purposes specified.

THOMAS H. HALLIDAY.
